UNITED STATES PATENT OFFICE.

WALTER H. UNDERWOOD, OF DENVER, COLORADO.

COMBINED MUCILAGE RECEPTACLE AND BRUSH.

SPECIFICATION forming part of Letters Patent No. 373,701, dated November 22, 1887.

Application filed January 20, 1887. Serial No. 224,853. (No model.)

To all whom it may concern:

Be it known that I, WALTER H. UNDERWOOD, of Denver, in the county of Arapahoe and State of Colorado, have invented certain new and useful Improvements in a Combined Mucilage Receptacle and Brush, of which the following is a specification.

The object of my invention is to provide a new and improved receptacle for holding mucilage, which receptacle is provided with a brush or rubber tip that is an equivalent for the brush, and which is to be used for applying the mucilage direct from the receptacle.

The invention consists of a receptacle made of metal, glass, or other material, of increasing diameter from both ends to a point between the ends, one end of the receptacle being closed by a soft-rubber cap and the other end by a soft-rubber tip, above which an aperture is provided, from which the mucilage can flow out of the receptacle and upon the tip and flow down the same to the paper. The said aperture can be closed by a rubber sleeve, all as will be fully described and set forth hereinafter, and finally pointed out in the claims.

In the accompanying drawings, Figure 1 is a longitudinal sectional elevation of my improved combined mucilage receptacle and brush in an upright position, the outlet-aperture being open. Fig. 2 is a sectional view of the same tilted as in use, the outlet-aperture being closed.

Similar letters of reference indicate corresponding parts.

The receptacle A is made of sheet metal, glass, porcelain, or other material, and is tapered from the two ends to a point between the ends, as shown at A' and A'', the taper A' being longer than the taper A''. At the ends of the tapered portions A' A'' the necks B' and B'' are provided, of which the former has the greater diameter. A soft-rubber cap, C, preferably hemispherical, is held upon the neck B', and a soft-rubber tapering tip, D, having an elastic flange, D', is held by said flange in the neck B''. Directly above the top of the flange D' the aperture F is provided in the side of the neck B'', which aperture has approximately the size of a pin-hole and serves

to permit the mucilage to pass from the receptacle A out upon the outside of the tapered tip D; or a slit may be provided in place of the pin-hole. A soft-rubber sleeve or band, G, on the flange D' and neck B'' serves to close 55 said aperture F when the mucilage is not to be used.

When the mucilage is to be used, the aperture must be opened by sliding down the sleeve or cover G. The receptacle A is held 60 in upright position and the cap C pressed inward so as to produce a pressure upon the surface of mucilage, whereby a small quantity of the mucilage is forced out of the aperture F, flows down the tip D, and onto the paper, 65 &c., over which the tip is drawn. When the flow of mucilage is to cease, the pressure is removed from the cap C. When the apparatus is not to be used, it is rested on its side and assumes the position shown in Fig. 2, the end 70 having the collar B' being weighted, so that when the receptacle is not held in upright position the weighted end—that is, the one provided with a collar, B'—will rest on the table or support on which the receptacle is placed. 75 The mucilage thus flows from the tip end to the opposite end of the receptacle, and cannot pass out through the aperture, as shown in Fig. 2. In place of providing the aperture closed by the rubber cap C, the same can be 80 provided in one side, as shown in dotted lines in Fig. 2.

The brush-tip may be made of flexible sheet metal, if desired.

Having thus described my invention, I claim 85 as new and desire to secure by Letters Patent—

1. The combination, with a receptacle increasing in diameter from its ends to a point between the ends, of a neck at one end of the receptacle, an aperture in the side of said neck, 90 and a rubber tip on said neck, substantially as herein shown and described.

2. The combination, with a receptacle increasing in diameter from its ends to a point between the ends, of a neck on said receptacle, which neck has an aperture, and a rubber tip in said neck, the receptacle being provided with another aperture closed by a flexible cap, 95 substantially as herein shown and described.

3. A receptacle increasing in diameter from 100

its ends to a point between the ends, one end of the receptacle being weighted more than the other, the receptacle being provided with an aperture and a tapered tip on the end opposite the one that is weighted, said receptacle being also provided with an additional aperture which is closed by a rubber cap, substantially as shown and described.

In testimony that I claim the foregoing as my invention I have signed my name in presence of two subscribing witnesses.

WALTER H. UNDERWOOD.
